STORM WINDOW HANGER

John J. Ebel, Stevens Point, Wis.

Application February 4, 1949, Serial No. 74,604

2 Claims. (Cl. 16—172)

1

This invention relates to window supports and the like, and particularly to hangers for storm windows.

The main object of my invention is to provide means for conveniently suspending a storm window adjacent to a conventional window in accurate position thereon.

Another object is to provide storm window hangers including a pair of supporting brackets for a storm window and a corresponding pair of pin holders upon the storm window itself having suspension pins adapted to engage with the brackets in predetermined manner to support the storm window.

A further object is to have storm window hangers of the character indicated in which the suspension pins of the pin holders are resiliently compressible for inserting the pins in corresponding apertured or slotted portions in the supporting brackets.

It is also an object to have the supporting brackets provided with inwardly and downwardly-inclined open slots for receiving the suspension pins of the storm window fixtures and also for allowing the storm window to be released simply by lifting the latter off the supporting brackets.

It is a practical object to provide the supporting brackets with upwardly-extending grooves leading to the lower ends of the slots therein to facilitate insertion of the pins into the slots.

In addition, it is, of course, an object to provide storm window hangers which are simple to make and apply, low in cost and effective in use.

Other objects and advantages of the invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a fragmentary elevation of a storm window illustrating one corner thereof and a corresponding corner of a window frame with a supporting bracket fixed upon the window frame and a corresponding pin holder fixed on the storm window with a pin projecting therefrom and engaging with the supporting bracket, the two parts upon the frame and the storm window forming hanger means embodying the invention in a practical form;

Figure 2 is a top plan view of the hanger means of Figure 1, as seen from above in the first figure;

2

Figure 3 is a section taken on line 3—3 in Figure 2;

Figure 4 is a right side elevation of the supporting bracket of Figure 1, as seen from the right in that figure;

Figure 5 is a perspective view of the pin holder of Figures 1, 2 and 3, with the suspension pin omitted therefrom.

In the views, the same reference numerals indicate the same or like parts.

Various expedients have been resorted to for attaching or suspending storm windows upon window frames and the like outside of conventional windows, but usually it has been necessary to make various adjustments, to use nails or screws and in different ways take extra steps and precautions to make each storm window fit upon the window frame where it is to be applied. When thus applying a storm window, it is usually a troublesome and more or less laborious task, and the same applies to the removal of storm windows in the spring after they have served their purpose through the winter. In some cases, such means have been used which have allowed storm windows pendently to be swung outward on temperate days to let in air and provide circulation and ventilation, and the fixtures used have ordinarily been screwed in place so that they must be unscrewed when the storm windows thus equipped are to be removed.

Upon considering this problem, it has occurred to me that a storm window should be conveniently set in place, should be pendently suspended so that the lower end can be swung out a distance from the window to which it is applied for ventilation on balmy days, and with all, should be easily removed without the necessity of using hammer or screw driver or any other tools.

As a result, I have succeeded in producing storm window hangers which serve the stated purpose, as will now be more fully explained.

Hence, in the practice of my invention, and referring again to the drawing, upon a window frame or the like 6 is fixed a hanger bracket 7 by means of a pair of screws 8, 8, the hanger bracket including a plate 9 from which a forwardly-extending supporting portion 10 projects at right angles thereto having a forwardly-open and rearwardly downwardly-inclined slot 11 therein terminating short of bracket plate 9 and adapted to receive and support a corresponding suspension pin 12 of a storm window, generally indicated at 13.

Upon the storm window is secured a pin holder 14 by means of screws 15, 15, while at the upper

end plate 14 is rolled into cylindrical form to provide a hollow cylindrical casing 16. In the cylindrical member 16 is located a compression spring 17 retained within the casing by means of a pair of inwardly-bent retaining fingers 18, 18 at one end thereof, while the pin 12 extends from the other end with the round main body portion 19 thereof slidably movable in the casing by spring 17 toward the opposite end, at which point a downwardly-bent stop finger 20 engages against the shoulder 21 formed on pin 12 by the termination of the fully round form of the main body or shank 19, beyond which the pin is flat, as indicated at 22, to provide a clearance for stop finger 20. Suspension finger 12 is thus depressible into casing 16 and as soon as released will be projected outwardly until shoulder 21 strikes stop finger 20.

Obviously, in the same manner as the corners at the left upon both the window frame and the storm window, which are illustrated as provided with the hanger bracket 7 and the pin holder 14, the opposite or right corners of both window parts are similarly provided in the opposite direction with a hanger bracket and the corresponding pin holder. Thus, if the storm window 13 is raised until it is at a sufficiently high level to dispose the pins 22 above the upper outer ends of the slots 11 in both hanger brackets 7, and this storm window then carefully maneuvered, both pins may be inserted into the slots 11 and the window allowed to gravitate inwardly toward window frame 6 and pins 22 seat in the lower ends of the slots, due to their downward and inward inclination. However, such maneuvering is not always convenient, and a simpler method of insertion of the pins and thereby effecting the suspension of the storm window may be provided.

For this purpose, each supporting bracket 7 upon the forwardly-extending plate 10 thereof is formed with a downwardly-extending and increasingly-deep slot substantially parallel to the forward face of window frame 6 and connecting with the lower end 24 of slot 11 in each case, the upper end of groove 23 at 25 being relatively shallow, and at the lower end 26 being quite deep. Upon the outer sides away from storm window 13, the forwardly-projecting bracket plates or portions 10 are correspondingly formed with inclined wall portions 27 formed by the groove 23. Thus, instead of raising the storm window 13 to register pins 12 with the upper ends of slots 11, it is but necessary to place first one pin in the lower portion of groove 23 substantially at 26, and then depress the pin thus seated in the groove until plate 14 meets the forwardly-extending portion 10 of hanger bracket 7 when the correspondingly-opposite pin 22 on the other opposite corner of the storm window will seat in the correspondingly-opposite groove 23. When both pins are thus seated in the deepest portions of the grooves 23, it is but necessary to push the storm window directly upward, when the pins will suddenly be released as soon as the lower ends 24 of slots 11 will be reached when the storm window will at once be supported and suspended from the pins engaging in the lower ends 24 of slots 11. The storm window thus suspended may readily be adjusted outwardly to any distance from the window at the lower end thereof to provide ventilation when required, and may also be readily removed from brackets 7 by simply lifting the window directly upward when the pins 22 will simply slide outwardly free from slots 11 due to the open upper ends thereof. If desired

the grooves 23 may be omitted and the pins 22 will then be introduced from the tops of the slots 11.

As shown and described, the hanger fixtures 5 for the storm window are simple to make and use, light in construction and effective to support the window.

Manifestly, variations may be resorted to and 10 parts and features may be modified or used without others within the scope of the appended claims.

Having now fully described my invention, I claim:

1. A hanger for storm windows and the like, 15 comprising a mounting bracket adapted to be secured to the window frame adjacent to a corner of the storm window, said mounting bracket including a substantially vertical flange provided in its top with a downwardly and rearwardly inclined slot being disposed near the vertical center of the flange, the flange being provided in its side adjacent to the storm window with a vertically extending groove having a side which is inclined so that the groove is deeper adjacent 20 to the bottom of the flange than near the top thereof, the groove leading from the bottom of the slot toward and through the bottom edge of the vertical flange, and a spring pressed element 25 adapted to be carried by the storm window adjacent to a corner thereof and adapted to engage within the groove of the flange and to slide upwardly therein while retracting, the element entering the slot at the top of the groove and 30 serving to suspend the storm window from the slot.

2. A hanger for a storm window, comprising 35 an L-shaped mounting bracket adapted to be mounted upon the window frame adjacent to a corner of the storm window and including a vertically disposed flange arranged adjacent to one vertical edge of the storm window, the vertical flange being provided in its top with an inclined slot, said slot having its bottom arranged near and above the vertical center of the flange, 40 the flange being provided below the bottom of the slot and in vertical alignment with the bottom of the slot with a substantially vertically extending groove, the groove extending from the bottom of the slot to the bottom edge of the vertical flange, 45 the groove increasing gradually in depth from the bottom of the slot to the bottom edge of the flange to form an inclined surface leading into the bottom of the slot, a pin carrier adapted 50 to be secured to the corner of the storm window adjacent to the mounting bracket, a transversely shiftable pin mounted upon the pin carrier, and a spring mounted upon the pin carrier and 55 engaging the pin to urge it transversely outwardly beyond the adjacent vertical edge of the storm window, the pin moving upwardly within the groove and being retracted by the inclined surface so that it may snap into the bottom of the slot in the vertical flange.
